UNITED STATES PATENT OFFICE.

ROBERT K. MCLELLAN, OF ROCHESTER, NEW YORK.

MECHANICAL MOTOR.

SPECIFICATION forming part of Letters Patent No. 709,644, dated September 23, 1902.

Application filed February 5, 1900. Serial No. 4,016. (No model.)

To all whom it may concern:

Be it known that I, ROBERT K. MCLELLAN, a citizen of the United States, residing at Rochester, in the county of Monroe and State 5 of New York, have invented a certain new and useful Improvement in Mechanical Motors, of which the following is a full, clear, and exact description, reference being made to the accompanying drawings, forming part 10 of this specification.

This invention relates to improvements in mechanical motors which embody shaft-driving mechanism and a main shaft, such as are shown and described in Letters Patent of the 15 United States No. 629,843, and a fly-wheel loosely mounted on and geared to the main shaft, as herein shown and as appears by an application about to be filed by Henry S. Durand for a patent for an improvement in 20 mechanical motors; and the invention consists of the combination, with the shaft and fly-wheel mounted thereon, of certain devices constituting a bearing for the fly-wheel and means for securing the fly-wheel in its proper 25 position on the shaft, substantially as described and claimed herein.

On the accompanying sheets of drawings, Figure 1 is a side sectional elevation of a motor embodying the invention; Fig. 2, a front 30 sectional elevation, on an enlarged scale, of fragments of the motor, the upper section being in the vertical plane containing the axis of the main shaft and the lower section in the vertical plane containing the axis of 35 the shaft shown in cross-section in Fig. 1 behind and below the main shaft; and Fig. 3, a cross-section of the main shaft and parts surrounding it in the plane xx , Fig. 2, viewed in the direction indicated by the arrows.

Similar reference-numerals designate like 40 parts in the different views.

The object of this invention is to provide the fly-wheel with a suitable ball-bearing and to render it easy to remove the fly-wheel, with 45 its bearing, from and replace and secure it in its proper position on the shaft and to remove the shaft from and replace it in the frame without disturbing the adjustment of the parts of the bearing.

The frame is a casting comprising the base 50 1 and uprights 10, connected together at their upper ends by a cross-bar and provided with

projections on their outer faces at the ends of the cross-bar 11, of which Fig. 1 shows a cross-section. The outline of each upright 55 viewed from the side is the same as that of the single upright shown in Fig. 1. In bearings on the lower and forward part of the frame is the shaft 2, which projects from the uprights or sides of the frame and on which 60 are the crank-arms 20, extending in opposite directions from the shaft, the crank-arms being connected by a pair of links to a pair of beams which are pivoted on the projections above mentioned at the ends of the 65 cross-bar 11 and which are provided at their lower ends with pedals, from which power is exerted by a person operating the motor is transmitted by the beams and links to the cranks. 70

The shaft 2 carries a large sprocket-wheel 21, which is affixed to the shaft by means of a set-screw 22, extending through the hub of the sprocket-wheel and into a groove in the shaft. Below and behind this shaft is another shaft 3, which is parallel to the shaft 2 and has bearings on the frame similar to those of the shaft 2. It carries a sprocket-ring 30, a sprocket-wheel 30', and a bevel-gear 31, which are fast on the shaft, the bevel-gear being close to one of the uprights, the sprocket-ring being near the inner face of the bevel-gear, and the sprocket-wheel 30' being close to the other upright. On the sprocket-wheel 21, which is in alinement with the sprocket-ring 30, and on this sprocket-ring is a chain 21', whereby motion is communicated from one sprocket to the other. A shaft 32—for example, a propeller-shaft having a bearing at the back of the frame—carries a bevel-pinion 34, which extends behind the sprocket-ring 30 and engages with the bevel-gear 31. 80 85 90

The diameter of the fly-wheel 4 is preferably such that the rim of the wheel extends below the level of the shaft 3, as shown, and 95 on the hub 4' of the wheel is a sprocket-ring 40, by means of which, together with the sprocket-wheel 30' and a chain 35, extending around and engaging with these sprockets, the fly-wheel is geared to the shaft 3. The hub of the fly-wheel contains bearing-rings 41 and 41'. These bearing-rings, in which are grooves that form parts of ball-channels, are pressed tightly into the hub 4'. On one 100 105

end of a sleeve 42, which is fluted at 42' next to its other end, as appears by Figs. 2 and 3, and which is longer than the hub of the fly-wheel, is fixed a bearing-ring 43, in which is 5 a groove that matches the groove in the bearing-ring 41 and forms therewith a complete ball-channel. A bearing-ring 43', screwed on the sleeve 42, contains a groove which matches that in the ring 41, and these grooves form 10 another ball-channel. The ring 43' extends over the fluted part 42' of the sleeve, and a set-screw 44, extending through the ring and into one of the grooves of the sleeve, locks the ring on the sleeve, and thus secures the 15 adjustment of the bearing, the balls 45 and 45' being confined in the ball-channels, as shown. In the sleeve which closely fits the shaft 2 and in the ring 43 is a groove 46, and in the shaft 2 is a pin 46', which fits in this 20 groove and attaches the sleeve to the shaft, the other end of the sleeve being in contact with the inner face of the sprocket-wheel 21. The fly-wheel, with the rings 41 and 41', travels on the balls 45 and 45', which roll on the 25 rings 43 and 43', these rings turning with the shaft 2 at a lower speed than that of the fly-wheel and rings 41 and 41', and the direction of the motion imparted to the fly-wheel from the shaft 2 is the same as that of the motion 30 of the shaft. The bearing is secured in the hub of the fly-wheel, and its parts are adjusted and locked together, as described, before the fly-wheel is put on the shaft. That end 35 of the shaft to which the crank-arm shown at the right of Fig. 2 is to be affixed is pushed through the upright shown at the left of the figure and through the sleeve 42 within the hub of the fly-wheel and through the sprocket-wheel 21 and the other upright, and when the 40 pin 46' is within the groove 46 the sprocket-wheel 21 is fastened to the shaft with its inner face against the sleeve 42. The shaft-bearings and loose crank-arm are applied to the shaft either before or after the sprocket-wheel 21 45 is fastened to it, and then by properly adjusting the shaft in its bearings by turning the bearing-cones on the shaft the sprockets 21 and 40 are brought into alinement with the sprockets 30 and 30', respectively, the distance 50 between the sprockets 21 and 40 being fixed and equal to that between the sprockets 30 and 30'.

To remove the fly-wheel or shaft from the frame, it is merely necessary to reverse the 55 operation described in the last paragraph.

Having thus described my invention, what I claim as new, and desire to secure by Letters Patent, is—

1. A mechanical motor comprising the combination of: a driving-shaft 2; a fly-wheel surrounding the driving-shaft; bearing-rings forming ball-channels within the hub of the

fly-wheel; balls in the ball-channels; a sleeve on the driving-shaft within said bearings and fly-wheel, the sleeve being capable of rotating with the driving-shaft; and mechanism to transmit motion from the driving-shaft to the fly-wheel; substantially as described. 65

2. A mechanical motor comprising the combination of: a driving-shaft 2; a fly-wheel surrounding the driving-shaft; bearing-rings fixed in the hub of the fly-wheel; a sleeve on the driving-shaft within the hub of the fly-wheel, the sleeve being capable of rotating with the driving-shaft; bearing-rings on said 70 sleeve; balls between the bearing-rings fixed in the hub of the wheel and those on the sleeve; and mechanism to transmit motion from the driving-shaft to the fly-wheel; substantially as described. 75

3. A mechanical motor comprising the combination of: a driving-shaft 2; a fly-wheel surrounding the driving-shaft; bearing-rings fixed in the hub of the fly-wheel; a sleeve on the driving-shaft within the hub of the fly-wheel, the sleeve being capable of rotating with the driving-shaft; means to attach the sleeve to the shaft; bearing-rings on said sleeve; balls between the bearing-rings fixed in the hub of the wheel and those on the 90 shaft; and mechanism to transmit motion from the driving-shaft to the fly-wheel; substantially as described. 85

4. A mechanical motor comprising the combination of: a driving-shaft 2; a fly-wheel; ball-bearings confined in the hub of the fly-wheel; a sleeve fitting on the shaft and extending through the hub of the fly-wheel and supporting the bearings; a gear-wheel on the shaft in contact with one end of the sleeve; a projection on the shaft, engaging with the sleeve at the other end thereof; and mechanism for transmitting motion from said gear-wheel to the fly-wheel; substantially as described. 95

5. A mechanical motor comprising the combination of: a driving-shaft 2; a fly-wheel 4 on said shaft; bearing-rings 41 and 41' fixed in the hub 4' of the fly-wheel; a sleeve 42 within the hub of the fly-wheel; bearing-rings 43 and 43' on said sleeve; balls between the bearing-rings fixed in the hub of the wheel and those on the shaft; a pin 46' in the shaft, fitting in the groove 46 in one end of the sleeve and in the bearing-ring 43; a stop on the shaft at the other end of the sleeve; a set-screw 44 extending through the bearing-ring 43' over the fluted part 42' of the sleeve; and mechanism for imparting motion to the fly-wheel; substantially as described. 110 115

ROBERT K. MCLELLAN.

In presence of—

JOHN E. DURAND,
CARRIE BAER.
